UNITED STATES PATENT OFFICE

WARD T. SIMPSON, OF GRAND RAPIDS, MICHIGAN, ASSIGNEE TO ALBERT G. DICKINSON, OF GRAND RAPIDS, MICHIGAN

CARBURETOR

Application filed September 8, 1924. Serial No. 738,655.

The invention concerns a system of supplying fuel to an internal combustion engine in which the usual vacuum tank is dispensed with and instead vacuum depression is created in the fuel bowl to draw fuel from a low level supply tank, and the invention consists in the features hereinafter described, and particularly pointed out in the claims:

In the drawings:

10 Figure 1 is a vertical sectional view in the nature of a diagram, some of the parts being displaced from their position in practice to make the view more comprehensive.

15 Fig. 2 is a side view of an automobile with my improvement attached.

20 In these drawings 1 is the fuel bowl into which fuel is led from a low level tank, through a strainer 2, a pipe 3, and a valve 4 which is controlled by a link 5 from a float 6 pivoted at 7. The fuel passes out from the bowl past a needle valve 8 and through a passage 9 to a tube 10 forming a part of the mixture nozzle which also includes an air tube 11 surrounding the fuel tube. The 25 needle valve is pressed by a spring 12 tending to force the valve to closed position, the open position of the valve being determined by any suitable means of adjustment.

30 The nozzle discharges into a mixing chamber 13 which is the cylindrical space above the nozzle and below the throttle valve. The mixing chamber at its upper end is directed to the engine intake and is coaxially arranged therewith. There is a vacuum passage 16 communicating the space in the fuel bowl above the fuel level with the engine intake, and the mixing chamber is in communication with this passage. The air tube 11 of the mixing nozzle directs primary air 40 to the restricted passage between the upper end of the fuel tube 10 and the adjacent wall of the air tube, and the air tube at its upper end, is flared outwardly to form a restricted secondary air passage at 17 between its outer 45 edge and the adjacent wall of a sleeve valve

18 slidably mounted within and against the inner side of the mixing chamber. This valve controls the admission of secondary air to flow along the outer side of the nozzle through the restricted space 17 to the mixing chamber, and for this purpose the valve moves towards and from the enlarged base 19 of the nozzle according to variations in the demand of the engine. The nozzle is provided with a frusto-conical tip and the result of the formation of the tip of the nozzle is to create a conical vacuum space above the nozzle which causes a flow of fuel therefrom by inducing a high velocity of primary air through the air nozzle.

50 A throttle valve 20 is pivotally mounted in the engine intake and any suitable connection is employed leading to within reach of the driver for operating it. This valve is connected with a valve 21 pivotally mounted in the air inlet 22, the connection being made by a link 23 so that both valves are operated in unison to open or close simultaneously.

55 At 24 is arranged a valve for the admission of hot air to the interior of the air tube of the mixture nozzle and to the mixing chamber when the sleeve valve 18 opens. This hot air valve opens inwardly against the pressure of the spring 25 which tends 70 constantly to seat it and this valve opens when the air valve 21 is closed and closes when the air valve 21 is opened, as will be further explained.

75 A starting valve is shown at 26. This is 80 rotatable in its seat and controls communication between a passage 27 leading to the engine intake above the throttle valve and the pipe 28, which leads to the bowl to receive fuel therefrom. This starting valve 85 may be operated by any suitable means. A port 29 extends to the pipe or passage 28 from the interior of the casing to supply air to said valve to compensate for any leakage 90 that may take place at said valve when

closed and to supply air to the fuel passing through said valve when in open position for starting, whereby said fuel will be atomized in some degree.

6 An automatic accelerator is employed to make the engine pick up quickly when, after having been started, the throttle valve is quickly opened. This mechanism involves a lower piston head 30 working in a well 31 to which the fuel has access through a port 32. The piston has a hollow stem 33 with a port 34 and the piston head 30 has a port 35. The piston is pressed downwardly by a spring 36 bearing against the upper piston head 37 and the top wall of the chamber 38 in which the upper piston works. This chamber is in communication by a passage 39, with the air intake of the engine at a point above the throttle valve. A fuel discharge pipe 40 leads from the lower part of the accelerator fuel well 31 through the passage 16 to discharge fuel just below the throttle valve 20. The outlet from this pipe is off to one side of the mixing chamber so that there will be no aspirating effect of the flow of mixture from the main nozzle thereon.

Operation

20 In starting the valve 26 is operated manually to open position, thus placing the engine intake at a point above the closed throttle valve in communication with the fuel bowl through the pipe 28. On cranking the engine, vacuum depression is created within the carburetor, which varies at different points, the greatest degree of depression being at the engine intake above the closed throttle valve 20. This will induce fuel to flow from the bowl through the pipe 28 and open starting valve 26 into the engine intake above the throttle valve. Air will pass through the passage 29 to mingle with the fuel on its way through the starting valve, to aid in atomizing the fuel as it merges into the engine intake.

Having started the motor, the starting valve 26 is closed by operating the manual connection. Fuel will now flow from the fuel chamber past the tapered needle valve 8, through passage 9 and tube 10 into the mixing chamber, this action being induced by the suction of the engine, it being understood that the throttle valve, even when closed, will leave sufficient opening to permit this suction to be exerted on the mixing chamber and nozzle, thus inducing an upward flow of air through the annular space within the air nozzle and the restriction 17 at the upper end of the same, due to slight rise of valve 18. This air is derived through the automatic valve 24, which opens under suction, and against the pressure of its spring. After passing the valve, the air reaches the space 42 through port 41. This

air, as above described, comes from a jacket or the like, arranged to be heated from the exhaust manifold so that soon after the engine is started the air entering the space 42 will be hot.

70 During the actions above described, the accelerating mechanism has been automatically set ready to deliver a charge of fuel to the engine intake as soon as the throttle valve is opened. The setting of the accelerating mechanism ready to act takes place by reason of the suction on the piston 37 exerted through the passage 39 from the port 43 located in the engine intake above the closed throttle valve. This suction raises 80 the piston against the pressure of its spring and fuel will now pass through port 32 into the well 31 and below the lower head 30 of the accelerating piston. It will be observed that with the throttle valve closed 85 there will be no substantial vacuum in the fuel chamber such as oppose the upward setting movement of the accelerator piston and the suction existing above the throttle valve will readily set the piston because it mainly has only to overcome the tension of the spring 36. Now, by quickly opening the throttle valve, there will take place an equalization of the vacuum depression between 90 the engine intake and the fuel chamber or 95 bowl and the spring 36 will now exert its force and move the piston down so that its lower head will press the fuel below it through the tube 40 to the engine intake to enrich the mixture for rapid acceleration. 100 If the throttle valve is opened slowly, instead of quickly as above described, the pulsation of the engine will be communicated through the passage 39, causing the piston to reciprocate and alternately pump fuel and 105 suck it back.

There is a critical point in the range of opening of the valve 20 at which the accelerating piston 30, 37 will tend to respond to the pulsations of the engine and produce this undesirable pumping action up and down of the piston. This critical point is when the throttle valve 20 has partly opened and thus partly broken the vacuum in the cylinder 38, thereby allowing the piston 30 to descend part way. When this position is reached the piston becomes sensitive to the pulsations of the engine and the undesirable reciprocating action would ensue if means were not provided to prevent it. To prevent this pumping action, the small openings 34 and 35 in the hollow piston rod and in the lower head of the accelerator piston, are provided. On the downward stroke of the piston, the fuel will rise through the port or opening 35 in the head of the piston and the fuel rising in the hollow stem of the piston forces air out through the opening 34 which thus acts as a breather hole.

If the throttle valve is closed for instance 110

in turning a corner, the suction will be cut off from the fuel chamber, but will exist in the passage 39 thus overbalancing the suction force in favor of lifting the piston against the tension of the spring, which lifting action now takes place, thus setting the accelerator for the quick pick up of the engine when the driver again opens the throttle valve after rounding the corner.

10 When the throttle valve 20 is opened, the connecting link 23 causes the valve 21 to open also. The degree of depression in the space 42 is decreased immediately to approximately atmospheric pressure and as a result the 15 spring 25 closes the ball check valve 24 to its seat thus shutting off the hot air at substantially the same time that cold air is admitted through the valve 21, the hot air no longer being desirable. When the valves 20 20 and 21 are opened the suction of the engine causes air to rush upward to the engine intake. This inrushing air passes up through the air nozzle 11 and past the tip of the fuel tube 10. The suction of the engine raises 25 the sleeve valve 18 from its opposing member or seat 19, thus opening the air inlet at 19^x, and air now rushes up through the valve 18 and past the restricted passage 17 between the flared upper end of the nozzle and the 30 sleeve valve 18, and the friction of the air against the inner side of the valve serves to lift it.

The main function of the sleeve valve is to maintain substantially a uniform vacuum 35 depression in the top of the fuel chamber for all speeds of the engine, to draw fuel from the low level storage tank into the fuel chamber 1.

I claim:

40 1. An apparatus of the kind described in which substantially equal pressures are maintained in the constant level fuel reservoir and mixing chamber by means of a direct communication between them, an ejector, a throttle valve, and means for automatically supplying fuel for quick acceleration, said means operating independently of the ejector and consisting of a piston for driving a charge of fuel from a well, said well being open 45 at its upper part to the area of low pressure above the fuel level in the reservoir and communicating with the reservoir below the normal level of fuel therein and with an outlet in the mixing chamber wall at a point elevated 50 above the normal fuel level, said piston having in its head a by-pass port and being joined by a rod to another piston on which a spring impinges, said spring being stressed by the suction of the engine when the throttle is closed, and released to force down the 55 pistons when the throttle is quickly opened.

60 2. In an apparatus of the kind described an acceleration device consisting of a chamber open to the fuel reservoir both below and above the normal level of fuel therein, and

containing two pistons joined by a rod, the space below the upper piston being that which opens into the fuel reservoir, the space above the upper piston communicating by a passage to the engine intake to be subjected to suction 70 when the throttle is nearly closed, said pistons being pressed by a spring above the upper one, the suction retracting said spring when the throttle is below said communication, the spring being released by the opening 75 of the throttle, and driving a charge of fuel from the lower part of the chamber out through a tube into the mixing chamber, the lower piston having a by-pass port through which fuel may pass, said by-pass port and the elevation of the outlet tube combining to prevent the emission of fuel from the tube when not intended, both fuel well and outlet tube being under the same pressure.

3. An apparatus of the kind described for supplying and carbureting fuel for internal combustion engines in which subatmospheric pressure is maintained for the primary purpose of lifting fuel from a main supply reservoir, this pressure being substantially the same in the fuel chamber of the apparatus and in the mixing chamber, which chambers are in open communication, and an ejector for forcing fuel into the mixing chamber and atomizing the fuel, and having as part 90 of its assembly a substantially cylindrical sleeve valve which by its weight controls the aforesaid pressure and by its movement admits air which joins with other air in the operation of the ejector, the cylindrical form 95 of said valve enabling it to rise without affecting the form of the passage it controls, and an accelerating device designed to operate independently of the ejector action and which is actuated by suction when the throttle is closed stressing a spring which drives 100 a piston against a charge of fuel when said suction is released by movement of the throttle, the said piston having a by-pass port cooperating with an outlet pipe terminating 105 high above the normal fuel level to nullify the effect of pulsations in the suction, said acceleration means being adapted to the substantially equal pressure surrounding it, and an anterior air valve operating in unison with 110 the throttle to govern the pressure below the ejector to permit this low pressure to actuate an alternative air inlet valve which is spring controlled and which leads to a source of hot air, said outer air inlet valves by their presence slightly intensifying, through the communication between mixing and fuel chambers, the subatmospheric pressure which lifts fuel, and permitting the use of a lighter sleeve valve than would otherwise be necessary.

4. In combination in a fuel supply system for internal combustion engines, a fuel chamber, an engine intake and mixing chamber in direct communication with the fuel chamber above the fuel level therein, a sleeve valve hav- 130

- ing a cylindrical interior, an ejector extending coaxially into said valve, having a fuel passage, said ejector having an outwardly flared enlargement at its end forming between itself and the cylindrical inner side of the sleeve valve an annular restriction for the passage of air, the area of said restriction being constant at all positions of the valve, said sleeve valve moving automatically along the mixing chamber under variations in the suction of the engine, and supplying more air below said restriction in accordance with its movement into the mixing chamber.

5. In combination in a fuel supply system for internal combustion engines, a fuel chamber, an engine intake and mixing chamber in direct communication with the fuel chamber above the fuel level therein, a sleeve valve having a cylindrical interior, an annular-seat 10 for said valve between which and the lower edge of the valve the air enters from all sides uniformly when the valve is raised, an ejector extending coaxially into said valve from said seat and having a fuel passage and a primary air passage, said ejector having an outwardly flared enlargement at its end forming between itself and the cylindrical inner side of the sleeve valve an annular restriction for the passage of secondary air, the area of said 15 restriction being constant at all positions of the valve, said sleeve valve moving automatically along the mixing chamber under variations in the suction of the engine, and supplying more air below said restriction in accordance with its movement into the mixing chamber.

6. In combination in a fuel supply system for internal combustion engines, a constant level reservoir communicating directly from its upper part with a mixing chamber, said communication permitting the maintenance of substantially equal pressures in both reservoir and mixing chamber, means for drawing fuel from the reservoir and delivering it 20 atomized into the mixing chamber, consisting of an ejector having a fuel tube and an air tube surrounding the same, a throttle valve at the engine intake, and two air inlet valves at the intake of the apparatus, one, spring 25 loaded, and operating automatically, the other, linked to the throttle and moving uniformly therewith, said ejector having an annular passage about it for secondary air, a sleeve valve controlling said annular passage 30 and operating automatically according to the vacuum depression in the mixing chamber, said two valves supplying air to said air tube and annular passage, substantially as described.

- 60 7. In apparatus of the kind described and in combination a mixing chamber and fuel chamber connected so that vacuum depression will exist over the fuel substantially equal to that in the mixing chamber, an ejector for 65 delivering fuel from the fuel chamber to the

mixing chamber, an accelerator consisting of a piston and cylinder for forcing fuel from the fuel chamber to the mixing chamber, a throttle valve, said cylinder being in communication with the fuel chamber, and in connection with the intake above the throttle valve, and a spring for forcing said piston to deliver fuel to the mixing chamber, substantially as described.

In testimony whereof I affix my signature. 75
